(57) **CLAIM**

The ornamental design for a connector, as shown and described.

DESCRIPTION

FIG. 1 is a top view of a connector according to the present design.

FIG. 2 is a side view of a connector of the design of FIG. 1. FIG. 3 is a front view of a connector of the design of FIG. 1.

FIG. 4 is a bottom view of a connector of the design of FIG. 1.

FIG. 5 is a side view of a connector of the design of FIG. 1. FIG. 6 is a rear view of a connector of the design of FIG. 1. FIG. 7 is a first perspective view of a connector of the design of FIG. 1 in a closed configuration; and,

FIG. 8 is a second perspective view of a connector of the design of FIG. 1 in an open configuration.

The broken line showing in FIG. 7 and FIG. 8 illustrates the environment of the claimed design and forms no part thereof.

1 Claim, 4 Drawing Sheets
